UNITED STATES PATENT OFFICE

ULRICH A. TADDIEN, OF PHILADELPHIA, PENNSYLVANIA, ASSIGNOR TO WESTINGHOUSE ELECTRIC & MANUFACTURING COMPANY, A CORPORATION OF PENNSYLVANIA

CONDENSER

Application filed July 5, 1929. Serial No. 376,018.

My invention relates to apparatus for condensing gaseous media and particularly to apparatus for condensing steam and it has for an object to provide apparatus of the 5 character designated which shall be highly effective and relatively small in proportion to its condensing capacity.

It has for still another object to provide a condenser which shall be well adapted to 10 be constructed in large sizes and which shall embody features of construction especially applicable to condensers of the radial flow and single pass types.

It has for a further object to provide a 15 condenser which shall have a relatively high heat transfer coefficient and which shall be capable of discharging the air and other non-condensable gases at a relatively low temperature and the condensed steam at a relatively 20 high temperature.

It has for still another object to provide a 25 condenser having a sectionalized tube nest so arranged as to render the entire tube surface highly effective for condensing purposes.

These and other objects are effected by my 30 invention, as will be apparent from the following description and claims taken in connection with the accompanying drawing, forming a part of this application, in which

Fig. 1 is a longitudinal view, in sectional elevation, of one form of condenser arranged 35 in accordance with my invention; and,

Fig. 2 is a transverse sectional view, taken on the line II—II of Fig. 1.

Referring now to the drawing, I show a 40 condenser provided with a shell structure 10 having an inlet 11 for steam to be condensed and an outlet 12 for discharging the condensate created in the shell structure. Associated with the outlet 12 is a hotwell 13 arranged in a manner well understood in the art. Secured to the ends of the shell structure are end tube sheets 14 and 15, and connected between the end tube sheets 14 and 15, 45 is a nest of cooling or condensing tubes 16.

As shown particularly in Fig. 2, the tube nest 16 is so formed, with relation to the 50 interior contour of the shell structure 10, that an intervening stream delivery space 17 is provided between the tube nest and the shell

structure, the steam delivery space 17 freely communicating with the inlet 11. As shown, the steam delivery space surrounds the entire tube nest, the tube nest not only being spaced from the side walls of the shell structure but 55 from the bottom wall as well. It is obvious, that the tube nest may be so arranged, with respect to the shell structure, that the steam delivery space 17 does not entirely surround the tube nest but only a substantial portion 60 thereof.

Secured to the tube sheet 14 is an inlet water box 18 provided with an inlet 19, while secured to the tube sheet 15 is a discharge water box 21 provided with an outlet 22, the water boxes 18 and 21 being preferably so arranged that the cooling water passes through the tube nest 16 in a single direction, the preferred embodiment illustrated in Fig. 1 being generally referred to as a single-pass 70 type of condenser.

In condensers of the larger sizes, the distances intervening between the end tube sheets 14 and 15 reaches such proportions 75 that some intermediate supporting means is required for the tube nest. Accordingly, in accordance with the prior art, I provide the required number of intermediate tube-supporting sheets and, in the present embodiment, I show by way of example, three intermediate supporting sheets 23, 24, and 25. The intermediate tube-supporting sheets 23, 24 and 25 are preferably so formed that their outer contours are similar to the contour of the tube nest and they are spaced 80 from the side walls or from both the side and bottom walls of the shell structure. The intermediate tube-supporting sheets 23, 24 and 25 divide the tube nest into a plurality of sections 26, 27, 28 and 29 all of which are 85 open and freely communicate with each other through the steam delivery space 17 and inlet 11.

Located within each of the tube nest sections is an air box 31 having top, bottom, 90 side and end walls and extending and fitting between adjacent tube sheets. Each air box 31 preferably forms a closed receptacle except for a plurality of air inlets 32 and an outlet conduit 33. Each air box 31 is so 100

disposed in its tube nest section that the air inlets 32 are disposed interiorly of the tube nest so that the gaseous media obtaining in the steam delivery space 17 may be said to be drawn radially inward from the periphery 5 of the tube nest toward a point near the central portion of the latter. Such a type of condenser is known as the radial flow type and is disclosed and claimed in U. S. Patent No. 1,142,784, issued June 8, 1915 to R. N. 10 Ehrhart and assigned to the Westinghouse Electric & Manufacturing Company.

Condensers of the radial flow type possess extraordinary advantages in that the steam is admitted to the tube nest from around 15 its entire or at least a substantial portion of its perimeter, thus greatly increasing the area of the admission space. Furthermore, the distance which the steam traverses across 20 the tube nest from the periphery or inlet toward the air outlet is reduced to a minimum and hence resistance to flow is lessened and the pressure drop is reduced, thus 25 conserving the kinetic energy of the incoming steam as much as possible. Furthermore, 30 the condensate leaving the outlet 12 is in contact with the incoming steam which is present in the lower portion of the steam delivery space 17 and consequently the condensate leaves the condenser at the highest possible temperature.

The intermediate tube-supporting sheets 23, 24 and 25 are preferably supported from the shell structure by means of suitable 35 brackets 34 while the air boxes 31 are supported from the lower portion of the shell structure by suitable bosses 35. Provided in each of the bosses 35 is a passage 36 communicating with the outlet conduits 33, and 40 the passages 36 connect through suitable pipe connections 37 with separate evacuating apparatus such as, for example, air ejectors 38. Each individual air ejector 38 is preferably 45 provided with an inlet 39 for the admission of motive fluid controlled by a valve 41, the arrangement being such that the capacity of each ejector may be individually regulated. All of the ejectors preferably 50 discharge, as illustrated, through a common conduit 42.

From the foregoing description, the operation 55 of my improved condenser will be apparent. Under normal conditions of operation, cooling water is admitted to the inlet 19 of the inlet water box 18, traverses the nest of cooling tubes 16 and leaves the condenser through the discharge water box 21 and outlet 22. Steam is admitted to the inlet 11 and surrounds the tube nest 16 in the steam 60 delivery space 17. As is evident, the cooling water in traversing the tube nest longitudinally, assumes progressively increasing temperatures in a direction from the inlet water box 18 toward the outlet water box 21. 65 Hence, the tube nest sections 26, 27, 28 and

29 assume progressively increasing temperatures and the section 26 may be referred to as a relatively cold section, and the section 29 as a relatively warm section. Hence, each of the respective sections has a gradually reducing condensing capacity in the direction 70 from the inlet water box 18 toward the discharge water box 21, assuming, of course, that the lengths of the respective sections, longitudinally, are somewhat alike.

As stated heretofore, each of the tube nest sections is provided with an air box 31 so arranged that the steam and non-condensable gases are withdrawn substantially radially from the periphery of the tube nest inwardly 75 toward the interior portion thereof. In the passage of the gases inwardly toward the interior portion of the nest, the steam is condensed and falls to the bottom of the shell structure and is discharged to the hotwell 80 13. The air and non-condensable gases enter the inlets 32 of the air boxes and are withdrawn by the ejectors 38. Inasmuch as the amount of steam entering the respective sections is, to some extent, dependent upon the 85 action of the air ejectors, the air ejector 38 associated with the relatively cold compartment 26 may be operated at greater capacity than the second or adjacent ejector located toward the warm end of the condenser and, 90 the latter or second ejector may be operated at a still greater capacity than the third ejector and so on. In this way, each section 26, 27, 28 and 29 acts, in effect, as a separate condenser and the amount of steam drawn in 95 to the several sections may be individually 100 regulated by their associated ejectors in accordance with the temperatures of their tube sections. In this way, the increasing temperature of the cooling water passing through 105 the tube nest is compensated for and the entire tube surface is made highly effective.

While, in the foregoing embodiment, I show a form of condenser wherein the tube nest is sectionalized and wherein only one tube nest section is associated with a single ejector, nevertheless it is to be understood that it is within the purview of my invention to have a lesser number of air ejectors than tube nest sections in which case each air 110 ejector is independently connected to a plurality of tube nest sections. Furthermore, while my invention is primarily applicable to condensers of the single pass and radial 115 flow types, nevertheless some of the features disclosed herein are equally applicable to condensers of other types.

In conclusion, it will be apparent that I have devised a condenser of the radial flow type provided with a sectionalized tube nest and having improved evacuating apparatus associated therewith so as to render the entire tube nest highly effective for condensing purposes.

While I have shown my invention in but

one form, it will be obvious to those skilled in the art that it is not so limited, but is susceptible of various changes and modifications without departing from the spirit thereof, 5 and I desire, therefore, that only such limitations shall be placed thereupon as are imposed by the prior art or as are specifically set forth in the appended claims.

What I claim is:—

- 10 1. In a condenser, the combination of a shell having an inlet for steam to be condensed and an outlet for condensate, a nest of tubes extending longitudinally through the shell and so spaced, with respect to the 15 side walls of the shell, as to provide an intervening steam delivery space surrounding a substantial portion of the nest, tube sheets and water boxes secured to the ends of the shell and providing for the circulation of 20 cooling media in a single direction through the nest, a tube sheet located intermediate of the ends of the nest and spaced from the side walls of the shell structure, said tube sheet dividing the tube nest, longitudinally, into 25 a plurality of sections freely communicating with each other through the surrounding steam delivery space, and independent means extending into the respective tube nest sections for evacuating the same.
- 30 2. In a condenser, the combination of a shell structure having an inlet for steam to be condensed and an outlet for condensate, a substantially cylindrical tube nest extending longitudinally through the shell structure, 35 said tube nest being spaced from the side walls of the shell structure so as to provide an intervening steam delivery space substantially surrounding the tube nest, tube sheets located at each end of the tube nest, an inlet 40 water box associated with one end of the tube nest and an outlet water box associated with the other end of the tube nest, said water boxes being so arranged as to provide for the passage of cooling water through the tube nest in a single direction, a tube support sheet 45 located intermediate the ends of the tube nest and dividing the latter, longitudinally, into a relatively cold section disposed adjacent to the inlet water box and a relatively warm, 50 section disposed adjacent to the outlet water box, means for supporting the intermediate tube sheet from the shell structure and providing for free and open communication between 55 the surrounding steam delivery space, separate air offtake means located near the cylindrical axis of each of the tube nest sections and evacuating means connecting with the respective sections and arranged to draw more steam 60 into the cold section than into the warm section.
3. In a condenser, the combination of a shell structure having an inlet for steam to be condensed and an outlet for condensate, 65 a tube nest extending longitudinally through the shell structure, said tube nest being spaced from the side walls of the shell structure so as to provide an intervening steam delivery 70 space substantially surrounding the tube nest, tube sheets located at each end of the tube nest, an inlet water box associated with one end of the tube nest and an outlet water box associated with the other end of the tube nest, said water boxes being so arranged as to provide for the passage of cooling water through the tube nest in a single direction, a tube support sheet 75 located intermediate the ends of the tube nest and dividing the latter, longitudinally, into a relatively cold section disposed adjacent to the inlet water box and a relatively warm section disposed adjacent to the outlet water box, means for supporting the intermediate tube sheet from the shell structure and providing for free and open communication between 80 the surrounding steam delivery space, separate air offtake means located near the cylindrical axis of each of the tube nest sections and evacuating means connecting with the respective sections and arranged to draw more steam 85 into the cold section than into the warm section.
4. In a condenser, the combination of a shell structure having an inlet for steam to be condensed and an outlet for condensate, a tube nest extending longitudinally through the shell structure, said tube nest being spaced from the side walls of the shell structure so as to provide an intervening steam delivery space surrounding a substantial portion of the nest, a tube sheet located at each end of the tube nest, an inlet water box associated with one end of the tube nest and an outlet water box associated with the other end of the tube nest, said water boxes being arranged 90 to direct the flow of cooling water in a single direction through the tube nest, a tube supporting sheet located intermediate the ends of the tube nest and spaced from the side walls of the shell structure, said tube sheet 95 dividing the shell structure into a plurality of sections all of which freely communicate with the surrounding steam delivery space, means for supporting the tube sheet from the shell structure, separate longitudinally-extending air offtakes fitting between adjacent tube sheets, and separate evacuating means connecting with the respective offtakes.
5. In a condenser, the combination of a shell structure having an inlet for steam to be condensed and an outlet for condensate, a tube nest extending longitudinally through the shell structure, said tube nest being spaced from the side walls of the shell structure so as to provide an intervening steam delivery 100 space substantially surrounding the tube nest, tube sheets located at each end of the tube nest, an inlet water box associated with one end of the tube nest and an outlet water box associated with the other end of the tube nest, said water boxes being arranged to direct the flow of cooling water in a single direction through the tube nest, a tube supporting sheet located intermediate the ends of the tube nest and spaced from the side walls of the shell structure, said tube sheet 105 dividing the shell structure into a plurality of sections all of which freely communicate with the surrounding steam delivery space, means for supporting the tube sheet from the shell structure, separate longitudinally-extending air offtakes fitting between adjacent tube sheets, and separate evacuating means connecting with the respective offtakes.
6. In a condenser, the combination of a shell structure having an inlet for steam to be condensed and an outlet for condensate, a tube nest extending longitudinally through the shell structure, said tube nest being spaced from the side walls of the shell structure so as to provide an intervening steam delivery 110 space substantially surrounding the tube nest, tube sheets located at each end of the tube nest, an inlet water box associated with one end of the tube nest and an outlet water box associated with the other end of the tube nest, said water boxes being arranged to direct the flow of cooling water in a single direction through the tube nest, a tube supporting sheet located intermediate the ends of the tube nest and spaced from the side walls of the shell structure, said tube sheet 115 dividing the shell structure into a plurality of sections all of which freely communicate with the surrounding steam delivery space, means for supporting the tube sheet from the shell structure, separate longitudinally-extending air offtakes fitting between adjacent tube sheets, and separate evacuating means connecting with the respective offtakes.
7. In a condenser, the combination of a shell structure having an inlet for steam to be condensed and an outlet for condensate, a tube nest extending longitudinally through the shell structure, said tube nest being spaced from the side walls of the shell structure so as to provide an intervening steam delivery 120 space substantially surrounding the tube nest, tube sheets located at each end of the tube nest, an inlet water box associated with one end of the tube nest and an outlet water box associated with the other end of the tube nest, said water boxes being arranged to direct the flow of cooling water in a single direction through the tube nest, a tube supporting sheet located intermediate the ends of the tube nest and spaced from the side walls of the shell structure, said tube sheet 125 dividing the shell structure into a plurality of sections all of which freely communicate with the surrounding steam delivery space, means for supporting the tube sheet from the shell structure, separate longitudinally-extending air offtakes fitting between adjacent tube sheets, and separate evacuating means connecting with the respective offtakes.
8. In a condenser, the combination of a shell structure having an inlet for steam to be condensed and an outlet for condensate, a tube nest extending longitudinally through the shell structure, said tube nest being spaced from the side walls of the shell structure so as to provide an intervening steam delivery 130 space substantially surrounding the tube nest, tube sheets located at each end of the tube nest, an inlet water box associated with one end of the tube nest and an outlet water box associated with the other end of the tube nest, said water boxes being arranged to direct the flow of cooling water in a single direction through the tube nest, a tube supporting sheet located intermediate the ends of the tube nest and spaced from the side walls of the shell structure, said tube sheet 135 dividing the shell structure into a plurality of sections all of which freely communicate with the surrounding steam delivery space, means for supporting the tube sheet from the shell structure, separate longitudinally-extending air offtakes fitting between adjacent tube sheets, and separate evacuating means connecting with the respective offtakes.

space surrounding a substantial portion of the nest, a tube sheet located at each end of the tube nest, an inlet water box associated with one end of the tube nest and an outlet water box associated with the other end of the tube nest, said water boxes being arranged to direct the flow of cooling water in a single direction through the tube nest, a tube supporting sheet located intermediate of the ends of the tube nest and spaced from the side walls of the shell structure, said intermediate tube sheet dividing the shell structure into a plurality of sections freely communicating with the surrounding steam delivery space, means for supporting the intermediate tube sheet from the shell structure, air offtake boxes extending between adjacent tube sheets, said air offtake boxes having top, bottom, side and end walls and provided with inlet and outlet openings, separate conduit means connecting with the outlet openings of the respective air offtake boxes, said conduit means extending through the lower portion of the shell structure, and independent evacuating apparatus connecting with the conduit means of the respective tube nest sections.

6. In a condenser, the combination of a shell structure having an inlet for steam to be condensed and an outlet for condensate, a tube nest extending longitudinally through the shell structure, said tube nest being spaced from the side walls of the shell structure so as to provide an intervening steam delivery space surrounding a substantial portion of the nest, a tube sheet located at each end of the tube nest, an inlet water box associated with one end of the tube nest and an outlet water box associated with the other end of the tube nest, said water boxes being arranged to direct the flow of cooling water in a single direction through the tube nest, a tube supporting sheet located intermediate of the ends of the tube nest and spaced from the side walls of the shell structure, said tube sheet dividing the shell structure into a plurality of sections all of which freely communicate with the surrounding steam delivery space, means for supporting the intermediate tube sheet from the shell structure, longitudinally-extending air offtake boxes located interiorly of each of the tube nest sections, means for supporting the air offtake boxes from the shell structure, and evacuating means connecting with the air offtake boxes and providing for drawing more steam into the tube nest sections adjacent the inlet water box than into the tube nest sections disposed adjacent the outlet water box.

7. In a condenser, the combination of a shell structure having an inlet for steam to be condensed, a tube nest extending longitudinally through the shell structure, said tube nest being spaced from the side walls of the

shell structure so as to provide an intervening steam delivery space surrounding a substantial portion of the nest, tube sheets and water boxes associated with the ends of the tube nest, tube supporting sheets located intermediate of the ends of the tube nest and dividing the tube nest, longitudinally, into a plurality of sections, said intermediate tube supporting sheets being spaced from the side and bottom walls of the shell structure, means for supporting the intermediate tube supporting sheets from the shell structure, a hot well communicating with the shell structure for receiving condensate from a plurality of tube nest sections, and separate and independent air offtake means for each of the tube nest sections.

8. In a condenser, the combination of a shell structure having an inlet for steam to be condensed and an outlet for condensate, a tube nest provided with end tube sheets and extending longitudinally through the shell, inlet and outlet water boxes associated with the ends of the tube nest and providing for the circulation of cooling water in a single direction through the nest, a tube supporting sheet located intermediate of the ends of the tube nest and dividing the latter, longitudinally, into a plurality of sections, and separate air-offtake means for the respective tube nest sections, each of said air offtake means having an inlet located in the interior of the tube nest section and in spaced relation, radially, with the periphery of the intermediate tube supporting sheet.

9. In a condenser, the combination of a shell structure having an inlet for steam to be condensed and an outlet for condensate, a tube nest provided with end tube sheets and extending longitudinally through the shell, an inlet water box associated with one end of the tube nest and an outlet water box associated with the other end of the tube nest, said water boxes being arranged to provide for the circulation of cooling water in a single direction through the tube nest, a tube supporting sheet located intermediate of the ends of the tube nest and dividing the latter, longitudinally, into a relatively cool section disposed adjacent to the inlet water box and a relatively warm section disposed adjacent the discharge water box, and evacuating means connecting with the respective tube nest sections, said evacuating means having an inlet located in an interior portion of each of the tube nest sections and in spaced relation, radially, with respect to the periphery of the intermediate tube supporting sheet and said evacuating means being arranged to draw more steam into the cold section of the tube nest than into the warm section.

In testimony whereof, I have hereunto subscribed my name this 27th day of June, 1929.

ULRICH A. TADDIKEN. 120
